UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR AN EYELET.

SPECIFICATION forming part of **Design No. 25,827, dated July 21, 1896.**

Application filed September 30, 1895. Serial No. 564,211. Term of patent 14 years.

To all whom it may concern:

Be it known that I, ELEAZER KEMPSHALL, a citizen of the United States, residing at Newton, in the county of Middlesex and State of 5 Massachusetts, have invented and produced a new and original Design for Eyelets, of which the following is a specification, reference being had to the accompanying drawings, showing a part thereof.

10 Figure 1 represents a view of an eyelet, showing my design. Fig. 2 represents a sectional view of the same.

The leading feature of my design is a flat flange extending outwardly from the outer 15 end of the tube or body of an eyelet and located in a plane at right angles to the said tube, and an annular upwardly-projecting lip on the outer margin of said flange.

a represents the tube or tubular body of an eyelet, and *b* represents the flange, which extends outwardly from one end of the tube and is in a plane at right angles with the axial center of the tube. 20

c represents the upwardly-projecting lip on the outer margin of the flange. 25

I claim—

The design for an eyelet substantially as shown and described.

In testimony whereof I have signed my name to this specification, in the presence of 30 two subscribing witnesses, this 6th day of September, A. D. 1895.

ELEAZER KEMPSHALL.

Witnesses:

C. F. BROWN,

A. D. HARRISON.
